FOOTWEAR

Robert T. Dawes, Hudson, Mass., assignor to
 Thomas Taylor & Sons, Inc., Hudson, Mass., a
 corporation of Massachusetts

Application March 13, 1935, Serial No. 10,833

1 Claim. (Cl. 12—146)

This invention pertains to footwear and to a method of making footwear, and relates more particularly to shoes or slippers of the so-called open shank or sandal type, wherein the front and rear portions of the upper are independent and completely separated at the shank portion of the shoe. At the present time there is a substantial demand for women's dress shoes and dance slippers of this type, and there is always more or less demand for open shank house slippers and similar articles of footwear. When, hereinafter, a "shoe" is referred to, it is intended thereby to include shoes, slippers, pumps, sandals, or other similar article of footwear.

In accordance with previous practice, the heel or rear end portion of the upper of such a shoe or slipper is assembled with the other parts and lasted in substantially the same way as the rear portion of uppers which are continuous from front to rear, but for shoes of the open shank or sandal type, this prior practice is unnecessarily complicated and expensive.

Customarily, the heel portion of a shoe upper includes a stiff counter member, which in welt, stitch-down, cemented, and McKay shoes is usually moulded substantially to shape prior to lasting, and which in turned shoes is caused to become stiff after lasting. This counter stiffener is depended upon in the completed shoe to hold the rear portion of the upper in proper shape.

In accordance with usual methods of shoe making, and in order that the quarter may be of such shape as to permit it to be lasted snugly about the curved heel of the last, the quarter is made of two separate pieces cut to proper contour and usually united by a seam extending vertically at the rear end of the shoe. To prevent gapping of this seam it is quite common to stitch a stay-piece over it. All of these operations are expensive and add substantially to the cost of the shoe, and since the seam at this point abuts against the hard, unyielding counter, it is difficult to make the seam lie flat and smooth, so that it tends to form a distinct welt at the rear of the shoe even though a stay is not used. This detracts from the desired neat and pleasing appearance of the shoe at this point.

While the forward and shank portions of shoes differ materially in shoes of different styles, the rear ends of shoes do not vary to so marked a degree, so that although anything like a standard contour for the forepart of a shoe upper would be out of the question, it is quite possible and permissible at least to approach such a standard contour for the heel end of shoes.

Taking advantage of this latter possibility, and with the objects of improving the appearance of shoes of the open shank type, and of facilitating their manufacture, while decreasing the cost, I have discovered, as the result of considerable experiment, that acceptable shoes of the open shank type may be made without resort to the lasting of the heel portions of individual shoes. Stated in other terms, I have found that the rear end portions of shoe uppers may readily be made, for example, from composite sheet material, including an appropriate stiffening element or medium, by blanking out from the sheet material a piece of proper dimensions and contour, moulding said piece (for example, in a properly shaped die under pressure) substantially to the desired final form of the rear end of the completed shoe upper, and then merely assembling this moulded and shaped member with and securing it to the shoe bottom structure in proper position and by any appropriate attaching means. Thus no lasting of the rear end of the shoe is required, the operation of attaching the moulded shape-retaining rear portion of the upper being carried out without special machinery and by relatively unskilled labor and with great rapidity. Moreover, since the moulded rear end portion thus prepared need have no seam, stay or other blemishing factor, the complete shoe is of finer and more desirable appearance than shoes made by usual methods.

In accordance with the present invention, the rear portion of the upper may comprise a lining, a stiffener medium or member, and an outer element—the lining and outer element each being of any appropriate material, such for example as leather, cloth, artificial leather, paper, synthetic fabric (such as those made from cellulose derivatives), lacquer, or phenol-condensation products. I contemplate that one or another of such constituent elements may be dispensed with by proper selection of the remaining element or elements. Further, while I here suggest the moulding of the sheet material in dies under pressure to form the rear member of the upper, I contemplate that such preshaped rear member may be made in other ways, all within the scope of the present invention.

Since in some of the more extreme styles of shoe the forepart of the upper comprises little more than a toe portion or a toe portion with one or more straps or other elements taking the place of the usual vamp, I contemplate, as within the scope of the invention, the employment of a pre-moulded toe end portion, made of material and

in accordance with substantially the same mode of procedure as the heel end portion of the upper, above referred to.

In the accompanying drawings, wherein I have disclosed certain desirable embodiments of the invention by way of example,

Fig. 1 is a side elevation of a shoe of the open shank type embodying my invention;

Fig. 2 is a rear elevation of the shoe of Fig. 1;

Fig. 3 is a plan view of a piece of composite fabric appropriate for use in making the rear end portion of a shoe upper, illustrating how portions of proper shape and contour may be cut therefrom;

Fig. 4 is a plan view, to small scale, illustrating the approximate shape of such a piece of material preparatory to moulding;

Fig. 5 is a vertical longitudinal section through the moulded rear member of a shoe upper made in accordance with the present invention;

Fig. 6 is a plan view of such moulded rear member;

Fig. 7 is a diagrammatic plan view of a shoe bottom having the forward part of the upper lasted in usual manner and having the rear part of the upper prepared and secured in accordance with the present invention;

Fig. 8 is a vertical section on the line 8—8 of Fig. 7;

Fig. 9 is a perspective view of a moulded rear portion of a shoe upper, illustrating one desirable construction;

Fig. 10 is a fragmentary section substantially on the line 10—10 of Fig. 9;

Fig. 11 is a perspective view of the moulded rear end portion of a shoe upper having its upper edge finished in a different way;

Fig. 12 is a fragmentary vertical section through a piece of composite material of modified construction useful in making my improved shoe;

Fig. 13 is a section substantially on the line 13—13 of Fig. 11;

Fig. 14 is a view similar to Fig. 5, but illustrating a modified construction for use in making stitch-down shoes;

Fig. 15 is a view similar to Fig. 14 showing a slightly different construction for stitch-down shoes;

Fig. 16 is a side elevation of a stitch-down shoe made in accordance with the present invention; and

Fig. 17 is a view similar to Fig. 7 but illustrating a cement lasted shoe.

Referring to the drawings the numeral 1 designates a shoe of the open shank type, here shown as a dress shoe, having the sole member 2, a high heel 3, and the forepart of the upper 4. This shoe also comprises the rear part 5 of the upper, which is wholly separate from and independent of the forepart 4, and which, as here illustrated, may be provided (preferably after moulding) with an appropriate strap 6 or other securing means.

In accordance with the present invention, the rear part 5 of the upper is made from sheet material S (Fig. 3) whose opposite sides are of a character appropriate to constitute the exposed inner and outer surfaces respectively of the portion of the shoe upper which it is intended to make. As illustrated in Fig. 3, this sheet material is of composite or lamellar type, comprising a plurality of layers permanently united to form an integral structure. This composite lamellar material preferably comprises a layer 7

adapted to form the outer surface of the member 5 in the completed shoe—a layer 9 appropriate to form the lining of the rear part 5 in the completed shoe, and an interposed layer 8 of an appropriate stiffening material capable of satisfactorily retaining a contour imparted by moulding pressure, for example a layer of leather, fiber board or the like; or alternatively a layer of felt or similar material impregnated with a suitable stiffener such as a thermoplastic binder, shellac or the like; or a sheet of material which is normally stiff and hard but which by suitable treatment may be made mouldable, for example, Celluloid or other cellulose derivative; or this stiffening medium may under certain circumstances consist merely of a layer of an appropriate adhesive substance having stiffening characteristics uniting and/or impregnating the layers 7 and 9 and imparting the desired stiffness and shape-retaining character to the composite fabric, for example, such a material might be a solution or a dispersion of one of the cellulose derivatives, shellac, chromated glue or the like.

This sheet material is prepared in lengths and widths of any desired dimensions, and if desired may be furnished to the shoe manufacturer in this form. From this sheet material, sections 10 are blanked out by any desired method or apparatus, for example, these pieces may be cut by hand by the use of patterns, or may be die cut out by the use of suitable dies in a dinking machine or the like—the pieces 10 each being of proper size to form a completed rear portion of the shoe upper. As suggested, these pieces may be cut by the shoe manufacturer according to his needs, or these pieces may be cut to the manufacturer's order, for example by a maker of shoe findings, and shipped to the shoe manufacturer either flat, or moulded ready for use in a shoe. Preferably the lower or straight edge of the piece 10 is provided with a series of indentations 11 to facilitate the operation of moulding the attaching flange.

Prior to the moulding operation, the stiffener layer or medium 8 is subjected to proper conditions to reduce it to a mouldable or ductile condition. For example, if this stiffener layer 8 be of fiber board; fabric impregnated with glue or paste; leather or the like, it may suffice merely to subject the piece to a moist atmosphere or to a tempering operation, such as is common in the manufacture of shoes, so as to reduce it to pliable condition. If Celluloid or similar material form the stiffener medium or element, it may be necessary to soak the piece 10 in a solvent for the Celluloid; and if a thermoplastic stiffener material be used, it may be necessary to soften it by the application of heat, either dry or moist in accordance with circumstances.

Having prepared the piece 10 for moulding as above suggested, it is then placed in an appropriate die having the approximate shape of the completed rear portion 5 of the shoe upper which it is desired to make, and the part is subjected to pressure with or without heat as is best adapted for the material employed, and by pressure within the die is reduced substantially to the final form indicated at 12 in Fig. 6, for example. Preferably the lower edge of this moulded shape 12 is provided with an inturned attaching flange 13. This flange may extend continuously around the lower part of the moulded shape, or may consist merely of separated tabs or the like, or may be replaced by any other suitable attaching element or elements. After moulding, the stiffener

8 resumes its normally stiff condition, thus permanently retaining the final finished shape imposed upon the sheet material during the moulding operation.

In making the shoe, the forward portion 4 of the upper may be lasted in accordance with any usual methods, so as to bring its lower margin 14 (Fig. 7) over against the lower surface of the insole 2^a, such margin being permanently secured in place by means of staples 15, cement, tacks or such other type of fastener as may be desired. The rear part 5 of the upper having been pre-moulded, as above described, requires no subsequent lasting operation to bring it to the desired final shape, but is merely assembled with the insole 2^a (at any convenient stage in the shoe making operation) so that its flange 13 overlaps the bottom of the insole, and this flange, or such equivalent attaching elements as may have been provided, is secured directly to the sole member by means of tacks 16, which, as illustrated in Fig. 8, are so driven as to be clenched against the usual steel plate P of the last L. This simple operation completes the assembly of the rear part 5 with the insole, and the outer sole may now be secured in place in any desired manner.

In the above description it has been assumed that the shoe comprises both inner and outer soles, but if the shoe be of a type which does not have a distinct outer sole, it is obvious that the rear portion 5 may be secured directly to such sole member as may be used, with its flange 13 disposed either below the sole member or above it, as circumstances may require. If the flange 13 be disposed above the sole member, the attaching tacks will then be driven downwardly through the flange and clenched at the under side of the sole member at the heel seat, or the flange may be attached by stitching or other equivalent fastening means.

In Figs. 9 and 10 a slightly modified construction is shown, in which the moulded rear portion 5^a is made from sheet material having but two distinct layers or component parts. Thus, as illustrated in Fig. 10, this moulded shape comprises the outer layer 7 which is of appropriate material to form the outer exposed surface of the rear part of the upper, and an inner layer 8^a which may itself be the stiffener layer but which is also of a material acceptable to form the lining of the rear part of the upper. For example, this layer may be fiber board having a smoothly finished inner surface, or it might be a layer of woven fabric impregnated with such a stiffening agent as a cellulose solution. As illustrated, this moulded shape has an attaching flange 13^a at its lower edge, while its upper margin is skived at 19 to form a thin edge giving a somewhat more finished appearance to the rear part of the upper.

In Figs. 11 and 13 a further modification is illustrated, wherein the moulded rear portion 5^b of the upper is provided with a binding strip 17 secured in place by a sewed seam 18. This binding strip may be of any desired material suitable to give a proper finish to the edge of the upper; for example, this binder may be ribbon so arranged as to provide a French cord effect, or it may be a thin strip of patent leather, or in fact any material appropriate for the purpose. This binding strip covers the exposed edges of the constituent layers of the material of which the moulded shape is formed, giving a rounded and more finished appearance, as shown in Fig. 13.

In Fig. 12 another modification of the sheet material is illustrated, comprising the inner layer 7^b

9, which may be of woven fabric, leather, or the like, suitable to form the lining at this part of the shoe—a layer 8 of a stiffening substance which may be of any of the types above suggested, and an outer layer 7^a appropriate to form the outer finished surface of the rear part of the upper, such outer layer 7^a being of lacquer or other similar substance applied in the form of a fluid or plastic to the surface of the layer 8, and which is then permitted or caused to become hard, such layer being so applied as to form an element of the sheet material before the part 10 is cut therefrom, or applied to the part 10 either before or after the latter is moulded.

I further contemplate that the rear part 5 may consist of a single integral unit of appropriate material, for example, one of the phenol-condensation products moulded to final finished shape and having its inner and outer surfaces appropriately finished to give the desired final effect in the shoe.

In shoes of the stitch-down type the lower margin of the upper is turned outwardly and directly united by stitches or the like to the marginal portion of the outer sole. To embody the present invention in shoes of this type, the rear end portion of the upper may be shaped as illustrated, for example, in Fig. 14. In this view the rear part 12^a is made in accordance with any of the procedures above outlined; for example, it may comprise the lining ply 9^a, the stiffener ply 8^a, and the outer or surface ply 7^a integrated and moulded to form a shape-retaining unit, as previously described. However, in this instance the flange 13^a is turned outwardly instead of inwardly. In making a stitch-down shoe, this flange 13^a rests upon the upper surface of the margin of the outer sole 20 (Fig. 16) to which it is united by stitches 21, staples, cement, or the like.

40 In the shoe illustrated in Fig. 16, the forepart 4^a may, if desired, be moulded from material similar to and in a manner substantially corresponding to that employed in making the rear part, and the outwardly directed flange 4^b may be united to the margin of the outer sole by stitches, staples, or the like in the same way as the rear part.

45 In a modified construction, illustrated in Fig. 15, the rear member 12^b of the upper, which comprises two or more plies, as previously described, is so moulded as to provide the outwardly turned attaching flange 13^b consisting of the united marginal portions of the outer and stiffening plies but having the lower margin 13^c of the inner or lining ply turned inwardly (forming in effect an inwardly directed flange) which rests upon the upper surface of the sole to which it may be united, for example, by paste or cement, and over the inner marginal flange 13^c a heel pad may be cemented in usual manner to provide the desired finish at the inside of the shoe. On the other hand, an outwardly directed flange 13^b is permanently secured to the sole member by stitches or the like.

50 55 60 65 70 75 In Fig. 17, which illustrates a cement-lasted shoe, the inwardly turned flange 13 of the rear part of the upper and the inwardly turned margin 14^a of the forward part of the upper are shown as overlapping the under surface of the insole 2^b to which they are secured by means of cement or other adhesive.

Various other modifications and equivalent arrangement of parts, as well as the substitution of other materials, will doubtless occur to those

skilled in the art and are regarded as coming within the purview of the invention as expressed in the appended claim.

I claim:

That method of making, as an article of manufacture, a unitary completed multi-ply shoe quarter ready for assembly as a unit with a sole member of a shoe and to form a finished part of the shoe upper without recourse to lasting, said method comprising as steps providing lamellar sheet material including plies, two of which are appropriate to constitute the exposed inner and outer surfaces, respectively, of said quarter, and one of which is normally of a shape-retaining nature capable of permanently retaining a contour imparted thereto by moulding pressure, cutting from said sheet material a blank of pre-determined appropriate contour, whose constitu-

ent plies are of the same size and shape, causing said blank to become mouldably plastic, moulding said blank under pressure to form a quarter having side walls and an end wall, the side walls 5 merging integrally and smoothly with the end wall, the moulding operation also forming an attaching flange joined integrally to the lower edges of the side and end walls and also imparting to the side and end walls substantially the exact 10 curved contour, in vertical planes at least of the quarter of a fully completed shoe, causing the material of the moulded end portion to become stiff and permanently retentive of the moulded shape imparted thereto, and at any suitable stage 15 in the process finishing the other edges of the rear and side walls so as to make such edges acceptable for exposure in a completed shoe.

ROBERT T. DAWES.
